UNITED STATES PATENT OFFICE.

CLARENCE R. ROBINSON, OF BROOKLYN, NEW YORK, ASSIGNOR TO ROBINSON FIBRE CORPORATION, OF WILMINGTON, DELAWARE, A CORPORATION OF DELAWARE.

APPARATUS FOR MANUFACTURING CONTAINERS.

Application filed March 22, 1924. Serial No. 701,108.

This invention relates to means and method of manufacturing containers, and more particularly to paper containers such as cups.

5 The objects of the invention are to provide improved means for manufacturing cups directly from pulp so the same will not have to be seamed or in any way joined, but may be made of one integral piece of paper or 10 board and thus obtain a cup which will be strong and will not leak; to provide means and method which will enable the cups to be made of uniform thickness; to provide a method and means by which the cups may 15 be shaped directly from pulp, dehydrated, dried and calendered as one continuous process; to provide for synchronizing the various mechanisms and operations, to secure simplicity of construction and operation and to 20 obtain other advantages and results as may be brought out in the following description.

Referring to the accompanying drawing in which like numerals of reference indicate similar parts throughout the several views, 25 the figure represents the apparatus and method for producing cups and similar articles in accordance with my invention.

In the specific embodiment of the invention illustrated in said drawing reference 30 numerals 1, 2 indicate mixing tanks having suitable agitators 3, 3 therein by means of which pulp of the desired consistency may be obtained. Both of these mixing tanks have outlets to a common conduit 4 with 35 control valves 5, 6 respectively by which a flow of pulp may be obtained from either mixing tank. In this way, a continuous supply of pulp may be had to conduit 4. Conduit 4 conveys the pulp to a movable 40 reservoir 7.

In order that said reservoir 7 may move up and down, as by means of cam 8, the conduit 4 is made telescopic, as at 9, beneath said reservoir. Above the reservoir is positioned a wheel 10 carrying a plurality of 45 perforated female forming dies or molds 11. Wheel 10 travels with a step by step movement, stopping every time a different die is positioned over reservoir 7. While the 50 wheel is thus standing still, cam 8 operates to elevate reservoir 7 so as to immerse the forming die 11 in the reservoir. Simultaneous with the immersion of said die in the reservoir, suction from a suction pipe 55 12 operating through axle 13 for the wheel,

communicates with a telescopic spindle 14 supporting the forming die and draws pulp against the interior surface of the forming die by virtue of the perforations therein connecting with the suction. It may be here 60 noted that the walls of the forming die are hollow and the interior surface only is perforated so the suction holds the pulp against the interior and not the exterior. After the cup has been formed the reservoir 7 is lowered and the wheel 10 advanced another step thus bringing another forming die 11 into position above the pulp reservoir. The suction continues to act upon the pulp within the forming dies for a portion of the revolution 65 of the wheel, thus both removing moisture from the pulp and retaining the pulp within the forming die against the walls thereof.

A second wheel 17 is mounted adjacent 75 wheel 10. This second wheel is similar in construction and operation to wheel 10 but instead of the female dies 11, is provided with exteriorly perforated male dies 16 adapted to receive the cups from the forming 80 dies 11. When wheel 10 is stopped, it is arranged that an actuating plunger 15 operates upon the telescopic spindle of one of the forming dies 11 which is in exact opposition to a die 16 on wheel 17. The plunger 15 85 causes the forming die 11 to place the article on die 16. At this time, suction within die 11 has been cut off and suction is applied within die 16 so that the article being formed from pulp is transferred to die 16. The 90 spindle 14 thereupon retracts and both wheels turn so the next dies come into opposition. During the period of interchange of the article being formed, the two wheels may be locked in exact position by any suitable 95 means such as the fluid control brake 18. Both wheels are furthermore operated in synchronism by any suitable drive such as the shaft and gearing indicated at 19.

As the dies 16 approach the top position 100 on wheel 17 they may be ejected laterally therefrom by any suitable means onto a carrier 20 provided with sockets 21 within which the supports 22 for the dies may be held against displacement while upon the 105 carrier. The die supports 22 are each provided with an external gear 23 and as the die and die support are carried along by the carrier said gear comes in contact with a rack 24 so that continued travel of the 110

carrier causes the die and die support to whirl. This may be carried on as long as found necessary in order to obtain a sufficient drying of the article.

- 5 The die is next carried into a housing 25 while it is still being whirled so that the outside of the article will engage the side of said housing to smooth and calender the article. After this operation it is passed around a 10 wheel to an upside down position and the article will drop off the die. When the die returns to a position opposite wheel 17 it is again returned to place upon the wheel by a transverse movement and is then ready to 15 receive another article.

Obviously detail changes and modifications may be made in the construction and use of my invention and I do not wish to be understood as limiting myself to the details shown 20 and described except as set forth in the following claims as construed in the light of the prior art.

Having thus described my invention, I claim:

- 25 1. An apparatus of the character described comprising synchronized wheels, means for forming an article on dies on one wheel, means for transferring the article from the die on the first wheel to a die on 30 the second wheel, a carrier adapted to receive the said second wheel die and article thereon, and means for whirling said die and article, while on the carrier, for drying, calendering and smoothing the article.
- 35 2. Apparatus for making pulp molded containers comprising the combination of a pair of synchronized die-supporting wheels, a double-walled die having a foraminous inner wall carried by one of the wheels, a 40 reservoir for pulp, means for immersing the double-walled die into the pulp in the reservoir, means for reducing the pressure in the space between the die walls to form a container within the die, a die having a foraminous outer face carried by the second wheel, means for moving the first-named die and 45 partly formed container over the second-

named die and withdrawing the first-named die, and means for exhausting the pressure within the second-named die while the two dies are in telescoping position whereby the partly formed container is transferred to the second-named die.

3. Apparatus for making pulp molded containers comprising the combination of a pair of synchronized die-supporting wheels, a die having a foraminous wall carried by one of the wheels, a reservoir for pulp, means for immersing the die into the pulp in the reservoir, means for reducing the pressure in the die to form a container therein, a receiving die having a foraminous wall carried by the second wheel, means for moving the first-named die and partly formed container into telescopic relation with the second-named die and withdrawing the first-named die, and means for exhausting the pressure within the second-named die while the two dies are in telescoping position whereby the partly formed container is transferred to the second-named die.

4. Apparatus for making pulp molded containers comprising the combination of a pair of movable die-supporting carriers, means for moving the carriers step-by-step in synchronism, a plurality of double-walled dies having foraminous inner walls carried by one of the carriers, a reservoir for pulp, means for elevating the reservoir to immerse one of the dies when the carrier is at rest, 80 means for reducing the pressure in the space between the die walls to form a container within the die, a die having a foraminous outer face carried by the second carrier, means for moving the first-named die and partly formed container over the second-named die and withdrawing the first-named die, and means for exhausting the pressure within the second-named die while the two dies are in telescoping position whereby the partly formed container is transferred to the second-named die.

In testimony whereof I affix my signature.
CLARENCE R. ROBINSON.

CERTIFICATE OF CORRECTION.

Patent No. 1,694,627.

Granted December 11, 1928, to

CLARENCE R. ROBINSON.

It is hereby certified that error appears in the printed specification of the above numbered patent requiring correction as follows: Page 1, line 25, after the word "represents" insert the word "diagrammatically"; and that the said Letters Patent should be read with this correction therein that the same may conform to the record of the case in the Patent Office.

Signed and sealed this 22nd day of January, A. D. 1929.

(Seal)

**M. J. Moore,
Acting Commissioner of Patents.**
